United States Patent Office

Des. 204,335
Patented Apr. 5, 1966

204,335

BOAT

Don W. Cartner, 8809 E. 59th St., Kansas City, Mo.

Filed Aug. 4, 1965, Ser. No. 86,429

Term of patent 7 years

(Cl. D71—1)

FIG. 1 is a top plan view of a boat showing my new design;

FIG. 2 is an elevational view of one side thereof;

FIG. 3 is an end elevational view thereof;

FIG. 4 is a top perspective view thereof; and

FIG. 5 is a perspective view showing the boat in its folded condition.

I claim:

The ornamental design for a boat, as shown and described.
